R. A. McCANN

RAILWAY TRAFFIC CONTROLLING APPARATUS

Original Filed March 1. 1924

INVENTOR:
R. A. McCann,
by A. Z. Vinal,
His Attorney.

UNITED STATES PATENT OFFICE.

RONALD A. McCANN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Original application filed March 1, 1924, Serial No. 696,344, Patent No. 1,629,832, dated May 24, 1927.
Divided and this application filed January 26, 1927. Serial No. 163,690.

My invention relates to railway traffic controlling apparatus, and particularly to apparatus of the type comprising train carried governing means controlled, by energy received from the trackway. More particularly my present invention relates to the trackway portion of such apparatus.

The present case is a division of my co-pending application, Serial 696,344, filed 10 March 1, 1924, for railway traffic controlling apparatus which has matured into Patent No. 1,629,832, dated May 24, 1927.

I will describe one form of trackway apparatus embodying my invention, and will then point out the novel features thereof in claims.

The accompanying drawing is a diagrammatic view showing one form of trackway apparatus embodying my invention.

20 Referring to the drawing, the reference characters 1 and 1^a designate the track rails of a stretch of railway track, over which traffic normally moves in the direction indicated by the arrow. These track rails are divided, by means of insulated joints 2, into a plurality of successive blocks, of which only one block A—C is shown in the drawing. The block A—C is similarly divided into a forward track section B—C and a rear track section A—B. Each of the sections is provided with a track relay designated by the reference character R with a suitable exponent and connected across the rails adjacent the entrance end of the associated section. Each such track relay is controlled by current supplied to the rails of the corresponding section from a battery B connected across the rails adjacent the exit end of the section.

40 Each track section is also provided with a track transformer designated by the reference character T with an appropriate distinguishing exponent and having its secondary 3 connected across the rails adjacent the exit end of the associated section in series with the track battery 13. The primary 4 of each such track transformer is constantly supplied with alternating current from terminals D and E of a suitable 50 source of energy not shown in the drawing. It follows that each section is constantly supplied with direct current for the control

of the track relay, and also with alternating track circuit current.

Located adjacent the entrance end of each 55 block is a polarized line relay. Only relay G^A associated with block A—C is illustrated in the drawing.

Each block is provided with a trackway signal designated by the reference character S with an appropriate exponent and controlled by the associated relay G. Each signal as here shown is a three-position semaphore signal capable of displaying a proceed, a caution or a stop indication. The 60 control of these signals forms no part of my present invention and is omitted from the drawing for the sake of simplicity. For present purposes it is sufficient to state that each signal S is so controlled by its associated relay G that when the corresponding block is occupied, the signal indicates stop; when the corresponding block is unoccupied but the block next in advance is occupied, the signal indicates caution; and when the 65 corresponding block and the next block in advance are both unoccupied the signal indicates proceed.

Associated with signal S^c are a pole changer P^c and a circuit controller K^c, the 70 functions of which will be described in detail hereinafter.

75 Relay G^A is provided with a circuit which passes from a suitable source of energy, such as a battery N, through pole changer P^c, wire 16, front contact 17 of relay R^B, wire 18, front contact 19 of relay R^A, wire 20, winding of relay G^A, wire 21, pole changer P^c and back to battery N. This circuit is closed only when relays R^A and R^B are both 80 energized, under which conditions relay G^A is supplied with current of one polarity, which I shall call normal polarity, when signal S^c indicates proceed or caution, and with current of the opposite polarity which 85 I shall call reverse polarity when signal S^c indicates stop.

90 Located at point B is an auxiliary relay J, connected across wires 18 and 21. This relay is responsive to reversals of the relative polarity supplied thereto.

100 Means are also provided for supplying the rails in parallel of each track section with a current which I will term a "loop"

current. For this purpose I provide each track section with an impedance 6 connected across the rails adjacent the entrance end of the section and a similar impedance 7 connected across the rails adjacent the exit end of the section. Section B—C is further provided with a similar impedance 8 connected across the rails at an intermediate point in the section. Loop current 10 is supplied to each section from a loop transformer designated by the reference character L with an exponent corresponding to the location. Secondary 9 of transformer L^B is connected with impedances 6 and 7 15 in section A—B. Primary 10 of transformer L^B is provided with a circuit which passes from terminal D of the source of alternating current through polar contact 32 of relay J, wire 33, front contact 34 of relay J, wire 35, primary 10, wire 36, polar contact 37 of relay J, and back to terminal E of the same source. It follows that section A—B is supplied with loop current of 20 normal or reverse relative polarity according as relay J is energized in the normal or reverse direction but that no loop current is supplied to section A—B when relay J is de-energized. The primary 10 of transformer L^C is constantly supplied with alternating current from terminals D and E. One loop circuit for section B—C passes from secondary 9 of transformer L^C through wire 40, circuit controller K^C operated by signal S^c, wire 41, impedance 6 in section 25 B—C, through both rails of the section in parallel to impedance 7, and wire 42 back to secondary 9 of transformer L^C. This circuit is closed only when signal S^c indicates proceed or caution, under which condition section B—C is supplied with loop current of normal relative polarity throughout the length of the section. A second loop circuit is provided for section B—C over which current flows from secondary 9^a of transformer L^C, through wire 44, impedance 8 in section B—C, through both rails of the section in parallel to impedance 6, wire 41, circuit controller K^C operated by signal S^c and wire 43 back to secondary 9^a of transformer L^C. This circuit is closed only when signal S^c indicates stop under which conditions section B—C is supplied with loop current of reverse relative polarity between impedances 6 and 8. 30 The trackway apparatus herein shown and described is capable of co-operation with train carried governing means not shown in the drawing in such manner that when the train occupies a stretch of track 35 which is supplied with track circuit current and with loop current of normal relative polarity a proceed indication is received on the train; when the train occupies a portion of track which is supplied with track circuit current and with loop current of reverse

relative polarity a caution indication is received on the train; and when the train occupies a portion of track to which the supply of either track circuit current or loop current is interrupted the train receives a stop indication. It follows that both the loop current and the track circuit current may be considered as train governing currents. 70

As shown in the drawing signal S^c indicates proceed and block A—C is unoccupied. Relays R^A and R^B are both energized and current of normal relative polarity is supplied to relay G^A and to relay J. Current of normal relative polarity is therefore supplied to the primary of transformer L^B. Sections A—B and B—C are each supplied with track circuit current and with loop current of normal relative polarity throughout the lengths of the sections. If, now, a train moving in the direction of the arrow enters block A—C such train will receive a proceed indication throughout the block. The operation of the apparatus would be the same were signal S^c at caution. 80 85 90

I will now assume that signal S^c is at stop, as would be the case if a train occupied the block to the right of point C. Pole changer P^C and circuit controller K^C are reversed and current of reverse relative polarity is supplied to relay G^A and to relay J. Current of reverse relative polarity is then supplied to primary 10 of transformer L^B so that the rails of section A—B are supplied with loop current of reverse relative polarity throughout their length. Furthermore circuit controller K^C is now reversed so that loop current of reverse relative polarity is supplied to the rails of section B—C between impedances 6 and 8, but no loop current is supplied to section B—C between impedances 8 and 7. If a train moves through block A—C under these conditions it will receive a caution indication from point A to impedance 8 in section B—C, and a stop indication from impedance 8 to point C. 100 105 110 115

It should also be pointed out that if one train occupies section B—C so that relay R^B is de-energized, relay J will also be open. No loop current is supplied to section A—B under these conditions and a following train would receive a stop indication throughout section A—B. 120

One feature of my invention is that the same two line wires extending throughout the block for the control of line relay G located at the entrance end of the block are utilized to control the relative polarity of the loop current supplied to the rear section of the block. 125

In the accompanying drawing I have shown my invention applied to a train controlling system in which the train carried governing means is controlled by track circuit current and loop current, but it should 130

be particularly pointed out that this specific arrangement is not essential.

Although I have herein shown and described only two forms of trackway apparatus embodying my invention, it is understood that various changes and modifications may be made therein within the scope of the appended claims without departing from the spirit and scope of my invention.

Having thus described my invention, what I claim is:

1. In combination, a stretch of railway track, trackway train governing means for said stretch including a first polarized relay, means for supplying said polarized relay with current of one relative polarity or the other, a second polarized relay connected in parallel with said first relay, and means controlled by said second polarized relay for supplying said stretch with train governing current of one relative polarity or the other.

2. In combination, a forward and a rear section of railway track, traffic governing means for said rear section including a polarized relay, a trackway signal controlled by traffic conditions in advance of said forward section, means responsive to the condition of said signal for supplying said relay with current of one relative polarity or the other, a second relay connected in parallel with said first relay and responsive to the relative polarity of the current supplied thereto, and means controlled by said second relay for supplying train governing current of one relative polarity or the other to the rails of said rear section.

3. In combination, a forward and a rear section of railway track, traffic governing means for said rear section including a polarized relay, a trackway signal controlled by traffic conditions in advance of said forward section, means responsive to the conditions of said signal for supplying said relay with current of one relative polarity or the other, a second relay connected in parallel with said first relay and responsive to the relative polarity of the current supplied thereto, means controlled by said second relay for supplying train governing current of one relative polarity or the other to the rails of said rear section, and means responsive to the condition of said signal for supplying train governing current of one rela-

tive polarity or the other to said forward section.

4. In combination, a forward and a rear section of railway track, traffic governing means for the rear section including a polarized relay, a first and a second track relay responsive to traffic conditions in the forward and the rear sections respectively, a trackway signal controlled by traffic conditions in advance of the forward section, a pole changer controlled by the signal, a circuit for the polarized relay including the pole changer and a front contact of each said track relay, a second polarized relay connected in parallel with the first polarized relay and the front contact of the second track relay, and means controlled by the second polarized relay for supplying train governing current of one relative polarity or the other to the rails of the rear section.

5. In combination, a forward and a rear section of railway track, traffic governing means for said rear section including a polarized relay, a trackway signal controlled by traffic conditions in advance of said forward section, means responsive to the conditions of said signal for supplying said relay with current of one relative polarity or the other, a second relay connected in parallel with said first relay and responsive to the relative polarity of the current supplied thereto, means controlled by said second relay for supplying the rails of the rear section with train governing current the character of which depends upon the direction of energization of such second relay, and means for supplying the forward section with train governing current the character of which depends upon the condition of said signal.

6. In combination, a forward and a rear section of railway track, traffic governing means for the rear section including a relay, a circuit for said relay controlled in accordance with traffic conditions in advance of the forward section, a second relay connected in parallel with the first relay, and means controlled by the second relay for supplying train governing current to the rails of the rear section.

In testimony whereof I affix my signature.

RONALD A. McCANN.
